BICYCLE CHAIN GUARD

Viktor Schreckengost, Cleveland Heights, Ohio, assignor
to The Murray Ohio Manufacturing Company, Nash-
ville, Tenn., a corporation of Ohio

Application December 2, 1957, Serial No. 48,745

Term of patent 14 years

(Cl. D90—5)

Fig. 1 is a side elevational view of a bicycle chain guard showing my new design, the dot-dash representation of a sprocket, chain, crank and pedal being for illustrative purposes only;

Fig. 2 is a top plan view thereof;

Fig. 3 is a front elevational view of Fig. 1;

Fig. 4 is a rear elevational view of Fig. 1; and

Fig. 5 is a fragmentary perspective view of the forward portion of the chain guard taken from above and at the right side.

I claim:

The ornamental design for a bicycle chain guard, substantially as shown and described.
